SHADE CORD LOCK

Melvin B. Benson, Jackson Heights, N. Y., assignor, by mesne assignments, to Mayfair Shade Corporation, New York, N. Y., a corporation of New York

Application February 26, 1935, Serial No. 8,241

1 Claim. (Cl. 24—132)

This invention relates to shade cord locks and more especially to cord locks for shades of the type which are raised by being rolled up from the bottom on itself through the medium of combined rolling and lifting cords.

An object of this invention is a cord lock which is simple in construction, efficient in operation and can be economically manufactured.

A lock embodying this invention comprises a plate having one end bent first at right angles to and then back over the remainder parallel thereto to form two parallel portions with an intermediate portion joining them. A tab integral with one of the parallel portions extends between corresponding edges thereof and has a curved extension lying between said parallel portions. A lever is pivoted at one end to the plate and is arranged to have its free end swing into clamping relation to said intermediate portion. The lock is mounted on any suitable support with both the parallel portions and the intermediate portion in vertical position so that the lever swings about a horizontal axis. The shade cords are passed vertically between the intermediate portion and the curved extension and the lever is held with its free end spaced slightly from the intermediate portion of the plate. The arrangement of the cords is such that the weight of the shade with which the cords are associated tends to move them upward. So long as the cords remain strictly vertical, the lever has no locking action, but if they are moved laterally to engage the end of the lever and then released, they pull the end of the lever toward clamping relation with the intermediate portion and thus are locked against further upward movement.

Other objects, novel features and advantages of this invention will become apparent from the following specification and accompanying drawing, wherein:

Fig. 1 is a perspective view of a shade partially broken away equipped with a cord lock embodying the invention;

Fig. 2 is a fragmentary enlarged view partially broken away of the shade shown in Fig. 1;

Fig. 3 is a plan view of the cord lock;

Fig. 4 is a side elevation thereof, and

Fig. 5 is a section on the line 5—5 of Fig. 3.

The shade shown in the drawing consists of a head 10 and a plurality of horizontally slightly spaced slats 11 which are interconnected in the well-known manner by strings 12. The slats 11 are supported from the head 10 in any suitable manner and a face plate 10a is also at-

tached to the head 10 and overlies the top slats. An operating cord 13 has its ends attached to clips 13a attached to the head and passes under the lower end of the shade and through grommets 13b in the head in the well-known manner for shades of this type.

A lock is provided for holding the operating cord in any desired position of adjustment of the shade. This lock is supported by the head 10 and comprises a plate 14 having one end bent first at right angles to and then back over the remainder to form a portion 15 parallel to the main portion and intermediate connecting portion 16. A tab 17 integral with the portion 15 is bent at right angles thereto and extends from the top edge of the portion 15 to the top edge of the main portion of the plate. A curved extension 18 of the tab lies between two parallel portions of the plate and defines a passageway with the intermediate portion 16. A lever 19 is pivoted at one end to the main portion of the plate 14 and is provided at its free end with a right angle projection 20 which is adapted to swing into clamping relation to the intermediate portion 16. A stop 21 is struck up from the plate 14 to limit swinging movement of the free end of the lever 19 away from the intermediate portion 16.

The lock is supported from the head 10 by screws 22 in a position in which all three portions are vertically arranged. The operating cords pass over the tabs 17 along an extension 18 and through the passageway defined by the extension 18 and intermediate portion 16 into position to be grasped by the operator.

With the operating cords in a strictly vertical position, they are free to move up and down through the passageway in the lock with the lever 19 remaining in an inoperative position. When it is desired to lock the shade in an intermediate or fully raised position, the cords are swung laterally to engage the projection 20 on the lever and are then released. They move upwardly for a short distance, carrying the lever with them until they are securely clamped between the end of the lever and the intermediate portion 16, whereupon the shade is locked. A straight downward pull on the cords moves the lever out of clamping relation and it then drops by gravity into engagement with its stop 21.

As will readily be apparent, the lock consists merely of two parts, namely, the plate and the lever, both of which can be easily and economically fabricated from sheet metal by the usual stamping and bending operations. The completed lock is easily actuated and efficiently clamps

the cords to hold the shade in any position of adjustment.

I claim:

5 A cord lock comprising an integral plate having two parallel portions joined by an intermediate portion perpendicular to said two portions, a tab extending from the top edge of one of said parallel portions into engagement with the top edge of the remaining parallel portion and constituting a cord guide, said tab having a curved 10 extension lying between said parallel portions and defining a cord passageway with said inter-

mediate portion, and a lever pivoted to one parallel portion at a point removed from the intermediate portion and being arranged to have its free end swing into position below said cord guide to clamp against said intermediate portion a cord passing downwardly from said cord guide through said cord passageway, said lever being normally maintained out of clamping position by gravity and being lifted into clamping position by frictional engagement with a cord extending through 10 said cord passageway. 5
